UNITED STATES PATENT OFFICE

2,063,993

SHOE-TURNING MACHINE

Andrew Eppler, Lynn, Mass., assignor to United
Shoe Machinery Corporation, Paterson, N. J.,
a corporation of New Jersey

Application May 5, 1933, Serial No. 669,568

17 Claims. (Cl. 12—57)

This invention relates to shoe-turning machines, and is herein illustrated as embodied in a forepart-turning machine of the type disclosed in United States Letters Patent No. 1,448,111, granted March 13, 1923, upon the application of Andrew Eppler. The machine disclosed in the above-mentioned Letters Patent is provided with a relatively stationary forepart-spreader member positioned upon one side of a turning post and a clamp for engaging the heel end of a shoe upon the opposite side of the turning post. In that machine, treadle-operated mechanism is provided for moving the clamp and also for moving the turning post at half the speed of the clamp in a direction to cause the clamp to draw the shoe over the end of the turning post to reverse the forepart of the shoe.

An object of the present invention is to provide an improved forepart-turning machine of the type under consideration.

In accordance with this object, features of the present improved machine consist in the provision of a power-driven shaft, mechanism driven by the shaft for effecting relative movement of the shoe-engaging members and an automatically operated reversing gear for reversing the drive of the shaft to return the shoe-engaging members to initial position. In the illustrated machine, provision is made for operating the reversing gear by one of the shoe-engaging members whereby the shoe-engaging members are returned to their initial positions after they have performed a shoe-turning movement. In addition, operator-controlled means is provided for reversing or stopping the drive of the shoe-engaging members at any point in their travel.

In the accompanying drawings illustrating the preferred form of the invention,

Fig. 1 is a side elevation of the improved machine;

Fig. 2 is a plan view enlarged of certain parts shown at the upper end of Fig. 1;

Fig. 3 is a view in front elevation of the upper portion of the machine;

Fig. 4 is a view in side elevation of the mechanism shown in Fig. 2;

Fig. 5 is a view in front elevation of the lower portion of the machine;

Fig. 6 is a view in side elevation of the lower portion of the machine;

Fig. 7 is a view in side elevation, showing certain of the shoe-engaging members in unclamped position; and

Fig. 8 is a view similar to Fig. 7, showing cer-

tain of the shoe-engaging members in clamped position.

The supporting structure of the machine consists of a hollow frame 10, upon which is mounted an extension or head 12. Trunnioned upon a pin 14 mounted in the upper end of the head 12 is a bracket 16 from which depend a pair of pivot pins 18. Each of the pins 18 carries a forwardly extending arm 20, and each of the arms 20 carries, upon its forward end, a downwardly extending member 22. Each of the members 22 is provided with a slot 24 (Fig. 3) whereby it may be adjustably secured by a threaded pin 26 and a clamping nut 28 to the member 20. The members 22 are shaped to receive the forepart of a shoe prior to turning, and they may be spaced toward or from each other to accommodate the width of the shoe by means of an adjusting screw 30 having two oppositely threaded portions 32 and 34, respectively. The screw 30 is itself held against axial movement by means of a collar 36 which is pinned upon the screw and which is held against endwise movement by a pair of flanges 38 which depend from the bracket 16. A collar 40 is threaded upon the threads 32 of the screw 30 and a similar collar 42 is threaded upon the threads 34. The collars 40 and 42 are shaped in the form of spherical segments. The collar 40 is received within a concave complementary recess formed in the arm 20 and is maintained in such recess by a similarly recessed cover plate 44. The collar 42 is maintained in similar engagement with the other arm 20 by a similar cover plate 44. The collars 40 and 42, together with the recesses within which they are received, constitute ball and socket joints which accommodate the pivotal movement of the arms 20 as the latter are adjusted inwardly and outwardly about the pins 18 by turning the screw 30. The normal position assumed by the bracket 16 under the influence of its own weight and of the weight of the parts which it carries is indicated in Fig. 4. In this position it is a simple matter to apply the forepart of an unturned shoe upon the members 22. However, it is desirable, during the operation of the machine, to latch the bracket 16 in the position shown in Fig. 1. Such latching is accomplished by means of a tooth 46 secured upon the bracket 16 and engageable with a detent 48 carried upon the end of a pin 50 which is slidably mounted in the head 12. A compression spring 52 tends to urge the detent 48 into latching engagement with the tooth 46. To provide for unlatching the detent, a knob 54 is provided upon the outer end of the pin 50 and is en-

gaged by a pair of ears 56 which straddle the pin 50 and which are carried upon a bell crank 58 fulcrumed upon a pin 60 secured in the head 12. To the other arm of the bell crank 58 is connected a link 62 which is pivoted at its lower end to a lever 64 fulcrumed upon a pin 66 secured in the head 12. Depression of the lever 64, as will later be pointed out, serves to release the detent 48 and thereby to unlatch the bracket 16, allowing the latter to assume the position shown in Fig. 4.

Secured upon the forward portion of the frame 10 is a bracket 70 having formed in it a guideway 72 for a pair of rack bars 74 and 76. The 15 rack bars are maintained within the guideway 72 by means of a cover plate 78. The rack bar 76 constitutes a turning iron or post and carries at its upper end a small convex roll 80 (Fig. 3). Secured upon the upper portion of the rack bar 20 74 is a bracket 82. The bracket 82 has two side walls which extend outwardly, on each side respectively, of the rack bar 74. A cover plate 83 is secured to each of these side walls and covers the space between them. The outer face of the 25 rack bar 74, the inner faces of the extended walls of the bracket 82 and the inner face of the cover plate 83 thus constitute a guideway within which the rack bar 76 is supported for sliding movement relatively to the rack bar 74. The bracket 82 is 30 guided for reciprocating movement by a pair of blocks 84 which slide in guideways 86, respectively. The guideways 86 are secured to the head 12. A pin 88 is securely fixed in the bracket 82 and is pivotally connected at its ends to the 35 blocks 84, respectively. The pin 88, in moving downwardly during the latter portion of its operative stroke, engages the lever 64 and unlatches the bracket 16. Secured to the bracket 82 is a clamping plate 90 and cooperating with the plate 92 is a clamp 92 pivotally carried upon the end of a curved lever 94 which is fulcrumed upon the pin 88. A lever 96 having an operating handle 98 is fulcrumed upon a pin 100 secured in the bracket 82. A link 102 is pivotally connected 40 at one of its ends 104 to the lever 96 and at its opposite end 106 to an extension of the lever 94. The clamping lever 94 is normally held in open position, as shown in Fig. 7, by a coiled spring 107 surrounding the pin 100 and arranged to urge the lever 96 in a clockwise direction as viewed 45 in that figure. The clamp may be closed by swinging the lever 96 upwardly in a counterclockwise direction to the position shown in Fig. 8. In order to maintain the lever 96 in this position, there is pivotally mounted upon an extension 108 of the lever 96 a pawl 110 which engages a ratchet 112 secured upon the bracket 82. The pawl 110 is urged into ratchet-engaging position by a coil 50 spring 114. It is apparent that by reason of the foregoing construction, the clamp 92 can be moved into clamping position by the handle 98 and will remain in that position until the pawl 110 is unlatched. In order to provide automatically for releasing the pawl 110 after the 55 completion of the turning operation, there is provided a downwardly extending finger 116 which is carried upon a pivot 118 secured in a bracket 120 mounted upon the outside of one of the guideways 86. The pawl 110 has formed upon it a projection 122 which, when the bracket 82 returns to its uppermost position, engages a notch 123 in the lower end of the finger 116 to unlatch the pawl 110. A second projection 124 upon the pawl 110 engages the finger 116 as the pawl is rocked and thereby pushes the finger 116 out of 60

the way to permit further upward movement of the bracket 82. By the time the projection 122 is thus released from the notch 123 the pawl 110 will be carried beyond the ratchet 112 so that the lever 96 will be enabled to swing into unlocking position. The finger 116 is yieldingly maintained in position to be engaged by the projection 122 by means of a spring 126, one end of which bears against an abutment 128 formed upon the finger 116, and the other end of which bears against an abutment 130 formed upon the bracket 120. 10

The rack bars 74 and 76 have rack teeth formed upon their lower portions, respectively. Meshing with the rack teeth upon the bar 74 is 15 a pinion 132 (Fig. 6) fixed upon a shaft 134 journaled in the bracket 70. A second pinion 136 is also fixed upon the shaft 134. The pinion 136 engages a gear wheel 138 having twice the pitch 20 diameter of the pinion 132. The gear wheel 138 is fixed upon a sleeve 140 which is journaled in a bearing 144 formed in the bracket 70. Secured upon the outer end of the sleeve 140 is a disk 146 and secured to the disk 146 by means of clamping bolts 148 is a second disk 150. The disk 150 is secured upon the outer end of a shaft 152 which rotates within the sleeve 140. Formed in the disk 150 are two arcuate slots 154 through which the clamping bolts 148 extend. The slots 154 enable the disk 150 to be adjusted relatively to the disk 146; that is, they enable the two disks to be clamped together in any desired position of rotary adjustment. Secured upon the inner end of the shaft 152 is a pinion 156 which meshes 30 with the rack teeth formed upon the bar 76. By reason of the above-described arrangement, the rack bars 74 and 76 are both driven from the shaft 134, the rack bar 76 being driven at half the speed of the rack bar 74. Furthermore, the initial position of the rack bar 76 relatively 40 to the rack bar 74 may be adjusted by rotating the disk 150 relatively to the disk 146. 35

The shaft 134 carries a worm wheel 158 (Fig. 5) which engages a worm 160 carried upon a shaft 162, one end of which is journaled in the bracket 45 10 and the opposite end of which is journaled in a housing 164 secured to the bracket 70. Within the housing 164 and mounted for free rotation upon the shaft 162, but held against axial movement relatively to the shaft, are a pair of bevel 50 gears 166 and 168 respectively. These bevel gear wheels are constantly driven in opposite directions by a bevel gear 170 which they both engage. The gear 170 is fixed upon the end of a shaft 172 which is driven through gears 174 and 176 by a motor indicated generally by the 55 numeral 178 secured upon the frame 10. The direction of rotation of the gear 170, as viewed in Fig. 5, is clockwise. As above stated, the gears 166 and 168 are driven constantly in opposite 60 directions and are freely rotatable upon the shaft 162. For communicating the drive of one or the other of these gears to the shaft 162, there is provided a clutch mechanism comprising a friction clutch disk 180 fixed to the gear 166 and a friction clutch disk 182 fixed to the gear 168. Cooperating with the clutch disk 180 and slidably keyed upon the shaft 162 is a friction clutch disk 184. A similar friction clutch disk 186 is also slidably keyed upon the shaft 162 and is engageable with the clutch disk 182. The clutch disk 180 is provided with a grooved hub 188 which is engaged by a pair of pins 190 carried in the forked end of an operating lever 192 pivotally mounted upon a pin 194 secured in the housing 70 75

164. The clutch disk 186 is similarly provided with a grooved hub 196 which is engaged by a pair of pins 198 carried in the forked end of an operating lever 200 which is pivotally mounted upon a pin 202 secured in the housing 164. Connecting the free ends of the levers 192 and 200 is a link 204. The effective length of the link 204 may be varied for purposes of adjustment, inasmuch as this link comprises a member threaded 5 in opposite directions and provided with a hexagonal portion 206 at its center for engagement with a wrench. For ordinary operating conditions the link 204 is so adjusted as to space the clutch disks 184 and 186 far enough apart to enable them to assume a neutral position wherein they are disengaged from the clutch disks 184 and 186, respectively. Both of the levers 192 and 200 are normally urged in a counterclockwise direction, as viewed in Fig. 5 by a tension spring 10 208. Secured within an extension 210 of the frame 10 (Fig. 6) is a pin 212 upon which is pivotally mounted a bell crank comprising a hub 213 and a pair of arms 214 and 216. Connecting the free end of the lever 200 and the bell 25 crank arm 214 is a link 218 which, like the link 204, may be adjusted for length. The spring 208, as a matter of convenience, is anchored to the hub 213; its direction of pull, however, is such that it exerts substantially no turning force directly upon the hub. It does, however, exert a turning force upon the hub through the lever 200, the link 218, and the arm 214. The bell crank arm 216 is pivotally connected through a pin 220 to an operating rod 222. The lower end 30 of the rod 222 constitutes a hook 224 which is engageable with the under surface of a treadle lever 226. The treadle lever 226 is fulcrumed upon a pin 228 mounted in the frame 10 and is urged normally to upward position by a tension spring 230. A link 231 has its lower end pivotally connected to the pin 220 and its upper end pivotally connected to one end of a lever 232 which is fulcrumed upon a pin 234 mounted in the bracket 10. The opposite end of the lever 232 is engaged by a pin 236 which is carried in the lower end 35 portion of the rack bar 74. Secured upon a pin 238 carried in the lower portion of the frame 10 is a bell crank lever 240 one arm of which is connected to a tension spring 242 which tends to rotate the bell crank 240 in a clockwise direction, as viewed in Fig. 5. The spring 242, like the spring 208 and merely as a matter of convenience, is anchored to the hub 213. The opposite end of the bell crank 240 is connected by a link 244 to the lower portion of the operating rod 222. It 40 is evident that depression of the treadle 226 will pull the operating rod 222 downwardly, thereby rocking the bell crank arms 216 and 214 in a clockwise direction, as viewed in Fig. 5, and through the link 218 will rotate both the levers 200 and 192 also in a clockwise direction, the effect of which movement will be to bring the clutch disk 184 into driving engagement with the clutch disk 186 and to move the clutch disk 186 further from driving engagement from the 45 clutch disk 182. The shaft 162 will now be driven in the direction of rotation of the gear 166, causing the pinions 132 and 156 to retract or lower the rack bars 74 and 76 respectively, the rack bar 74 being retracted at half the speed of the rack bar 76. The operator can stop the machine at any time by releasing his pressure upon the treadle 226 sufficiently to enable the spring 208 to move the clutch disk 184 and 186 into 50 neutral position. Furthermore, the operator 55 may, if he desires, release his pressure upon the treadle 226 to a sufficient extent to enable the spring 208 to move the clutch disk 186 into operative engagement with the clutch disk 182 and thereby to cause the drive of the shaft 162 to be 5 reversed and the rack bars to be raised. If, however, the operator continues the downward movement of the rack bars, the lower end of the rack bar 76 will eventually engage a pin 246 adjustably threaded in the bell crank 240 and such 10 engagement will rotate the bell crank 240 in a counterclockwise direction (Fig. 5) causing the link 244 to pull the rod 222 to the left so that the hook 224 will be released from engagement with the treadle 226. The tension of the spring 208 15 will now shift the clutch disks 184 and 186 into reverse position inasmuch as the bell crank arms 214 and 216 are now free to swing in a counterclockwise direction, as viewed in Fig. 5. The rack bars 74 and 76 will then be raised until the 20 pin 236 engages the lever 232, the effect of which will be to lower the link 231 and the operating rod 222, thereby moving the bell crank arms 216 and 214 in a clockwise direction and through the link 218 shifting the clutch disks 184 and 186 25 into neutral position.

Secured upon the outer face of the rack bar 76 is an angle piece 248 for supporting the toe end of a shoe while the shoe is being positioned in the machine. The angle piece 248 occupies a 30 position directly beneath the ends of the spreader members 22 when the rack bar 76 is at its uppermost position. When the rack bar 76 is adjusted upwardly or downwardly relatively to the rack bar 74, it is necessary to make a compensatory 35 adjustment of the angle piece 248 and the angle piece is accordingly provided with a slot 250 to accommodate a clamping bolt whereby the angle piece may be secured in adjusted position. The machine is also provided with a switch box 252 40 housed within the frame 10 and accessible through an opening therein. A switch for controlling the stopping and starting of the motor 178 is secured within this switch box. There is also a fuse box 254 secured within the frame 10. 45 As an alternative to the motor 178, the machine may be driven through a pair of fixed and loose pulleys 256, 258 mounted directly upon the shaft 172 and indicated in Fig. 6. Secured upon opposite sides of the frame 12 respectively are a 50 pair of work-holding trays 260 positioned at a height convenient to the operator.

In the operation of the machine, an unturned shoe S is placed upon the downwardly extending fingers 22, the toe of the shoe pointing downwardly and the fingers extending within the forepart of the shoe. The fingers 22 are then pushed inwardly from the position indicated in Fig. 4 to the position indicated in Fig. 1 and they are retained in this position by the detent 55 48. The rack bars 74 and 76 are in their uppermost position, and the angle piece 248 will be directly beneath and will support the toe end of the shoe. The shoe is now bent over the roll 80 on the upper end of the rack bar 76, and 60 the heel portion of the shoe, which is still unturned, is clamped between the members 92 and 90. Fig. 1 shows the machine with the shoe thus clamped and in readiness for the turning operation. The operator now depresses the 65 treadle 226, causing the heel clamping members to descend at twice the speed of the turning post rack bar 76. The effect of this relative movement of the shoe engaging members will be to draw the heel end of the shoe downwardly 70 75

and to cause the shoe to be turned over the roll 80 on the upper end of the bar 76. It will be noted that the pressure of the operator's foot upon the treadle 226 is transmitted to the 5 clutch disk 184 and that the operator may slacken this pressure, if he so desires, to avoid straining the shoe, and, on the other hand, he may apply as much pressure as he desires to effect the turning operation. Shortly after the 10 shoe has been completely turned, the pin 88 will strike against the lever 64, pulling downwardly upon the rod 62 and releasing the detent 48, thus permitting the spreader fingers 22 to swing into position indicated in Fig. 4. Further downward movement of the rack bar 74 causes the 15 drive of the machine to be reversed through mechanism which has already been described, thereby returning the rack bars to their initial upward positions. As the bracket 82 moves upwardly the heel clamping members will be automatically disengaged and opened by previously described mechanism and the shoe with the forepart now turned may be removed from the machine.

25 Having described my invention, what I claim as new and desire to secure by Letters Patent of the United States is:

1. A shoe-turning machine comprising a plurality of shoe-engaging members constructed and 30 arranged for relative movement to turn a shoe, a power driven shaft, mechanism driven by said shaft for effecting said relative movement, a reversing gear for determining the direction of drive of said shaft, means acting upon said reversing gear to cause said shaft to be driven normally in a direction to effect an operative movement of said shoe-engaging members, and means for causing said reversing gear to reverse the drive of said shaft to effect a return movement of said shoe-engaging members.

2. A shoe-turning machine comprising a plurality of shoe-engaging members constructed and arranged for relative movement to turn a shoe, power driven mechanism for effecting said 45 relative movement, a reversing gear included in said power driven mechanism, and means operated by one of said shoe-engaging members for reversing said gear to return said shoe-engaging members to their initial positions after 50 they have performed a shoe-turning movement.

3. A shoe-turning machine comprising a plurality of shoe-engaging members constructed and arranged for relative movement to turn a shoe, power driven mechanism for effecting said relative movement, and operator-controlled means for reversing the drive of said power driven mechanism at any point in the travel of said shoe-engaging members.

4. A shoe-turning machine comprising a plurality of shoe-engaging members constructed and arranged for relative movement to turn a shoe, power driven mechanism for effecting said relative movement, a reversing gear included in said power driven mechanism, operator-controlled means for reversing said gear at any point in the travel of said shoe-engaging members, and means operated by one of said shoe-engaging members for reversing said gear to return said shoe-engaging members to their initial position after they have performed a shoe-turning movement.

5. A shoe-turning machine comprising a plurality of shoe-engaging members constructed and arranged for relative movement to turn a

shoe, a shaft, a pair of clutch elements slidably keyed upon said shaft, a pair of clutch elements freely rotatable upon said shaft, means for holding said rotatable clutch elements against axial movement upon said shaft, a gear wheel secured 5 to each of said rotatable clutch elements, a driven gear wheel meshing with each of the first-mentioned gear wheels to drive the rotatable clutch elements in opposite directions, means for shifting both of said keyed clutch 10 elements in unison to cause one or the other of said keyed clutch elements to engage one or the other of the driven rotatable clutch elements, thereby to cause said shaft to be driven in one direction or the other, and driving connections from said shaft to said shoe-engaging means.

6. A shoe-turning machine comprising a plurality of shoe-engaging members constructed and arranged for relative movement to turn a shoe, 20 driving mechanism for said shoe-engaging members, a reversing gear for said driving mechanism constructed and arranged to start, stop and reverse the drive of said shoe-engaging members, and operator-controlled means for controlling, 25 through said reversing gear, the drive of said shoe-engaging members.

7. A shoe-turning machine comprising a plurality of shoe-engaging members constructed and arranged for relative movement to turn a shoe, 30 driving mechanism for said shoe-engaging members, a reversing gear for said driving mechanism constructed and arranged to start, stop and reverse the drive of said shoe-engaging members, means operated by one of said shoe-engaging 35 members, when said shoe-engaging members have completed a shoe-turning movement, to cause said controlling means to reverse said reversing gear to return the shoe-engaging members, and means operated by one of said shoe-engaging 40 members, when the shoe-engaging members have been returned to their initial position, to cause said reversing gear to stop the drive of the shoe-engaging members.

8. A shoe-turning machine comprising a turning post, means for holding a forepart of a shoe at one side of said turning post, a pair of heel clamping members at the opposite side of said turning post, means for moving said turning post and said clamping members relatively to said 50 forepart holding means in a direction to turn the forepart of the shoe, a friction clutch included in said moving means, and operator-controlled means for varying, during the relative movement of said turning post and clamping members, the 55 force transmitted through said friction clutch, whereby the operator can control the force exerted upon the shoe.

9. A shoe-turning machine comprising a plurality of shoe-engaging members constructed and 60 arranged for relative movement to turn a shoe, one of said members consisting of a clamp for clamping a portion of the shoe, driving means connected to said clamp for effecting said relative movement, means for locking said clamp in 65 clamped position, and means operated by said driving means for unlocking said locking means to release the turned shoe from said clamp.

10. A shoe-turning machine comprising a plurality of shoe-engaging members constructed and 70 arranged for relative movement to turn a shoe, one of said members consisting of a clamp for clamping the heel end of a shoe, a spring for opening said clamp, manually-controlled means for locking said clamp closed against the pressure of 75

said spring, driving means connected to said clamp for effecting a relative operative movement and a relative return movement of said shoe-engaging members, and means operated by said driving means at the completion of said return movement to unlock said locking means to release the turned shoe from said clamp.

11. A shoe-turning machine comprising a turning post, means for holding the forepart of a shoe at one side of said post, a pair of heel clamping members at the opposite side of said post, and power driven mechanism for moving the clamping members and the post to turn the shoe over the post, one of said heel clamping members being constructed and arranged to be moved manually and independently of said power driven mechanism into a position to clamp a heel of a shoe against the other clamping member.

12. A shoe-turning machine comprising a turning post, means for holding the forepart of a shoe at one side of said post, a pair of heel clamping members at the opposite side of said post, a treadle, power driven mechanism controlled by said treadle for imparting to the clamping members and the post operative movements to turn the shoe over the post and return movements to restore the clamping members and the post to their initial positions, and means associated with said power driven mechanism for stopping the return movements of the clamping members and the post independently of the treadle upon completion of a cycle of movement.

13. A shoe-turning machine comprising a turning post, means for holding the toe of a shoe stationary at one side of said post, means for engaging the heel end of a shoe upon the opposite side of said post, power driven mechanism for moving the heel engaging means and the turning post at different speeds to turn the shoe over the post, and means actuated by said power driven mechanism upon the completion of a shoe-turning movement to reverse the drive of the power driven

mechanism to return the heel-engaging means and the turning post to their initial positions.

14. A shoe-turning machine comprising a plurality of shoe-engaging members constructed and arranged for relative movement to turn a shoe, mechanism including gear wheels in fixed relation to each other for driving said shoe-engaging members respectively to cause the shoe-engaging members to turn a shoe, and means for adjusting one of said gear wheels by rotating it independently of another gear wheel, thereby to adjust the operating position of one of said shoe-engaging members relatively to another shoe-engaging member.

15. A shoe-turning machine comprising a plurality of shoe-engaging members constructed and arranged for relative movement to turn a shoe, driving mechanism for said shoe-engaging members, a reversing gear in said driving mechanism for causing said shoe-engaging members to be returned to their initial positions, and an operator-controlled friction clutch in said driving mechanism for varying the force transmitted to said shoe-engaging members.

16. A shoe-turning machine comprising a turning post, means for holding the forepart of a shoe at one side of said post, a pair of heel clamping members at the opposite side of said post, power driven mechanism for moving the clamping members and the post to turn the shoe over the post, and means operable prior to the starting of said power driven mechanism for locking said clamping members in clamped position.

17. A shoe-turning machine comprising a turning post, means for holding the forepart of a shoe at one side of said post, a pair of heel clamping members at the opposite side of said post, a ratchet mechanism for locking said clamping members in clamped position, and power driven mechanism for moving the clamping members and the post to turn the shoe over the post.

ANDREW EPPLER.
